JOHN E. WOOTTEN, OF READING PENNSYLVANIA.

Letters Patent No. 82,672, dated September 29, 1868.

DRAUGHT-VALVE IN RAILROAD-CAR STOVES.

The Schedule referred to in these Letters Patent and making part of the same.

TO ALL WHOM IT MAY CONCERN:

Be it known that I, JOHN E. WOOTTEN, of Reading, Berks county, Pennsylvania, have invented an Improved Mode of Controlling the Temperature of Railroad-Cars; and I do hereby declare the following to be a full, clear, and exact description of the same

My invention consists of a deflector so combined with the air-heating space of a railroad-car stove or heater, and with the delivery-pipes or orifices connected therewith, that when the car is in motion, the said deflector can be made to control the temperature of the car, substantially as described hereafter.

In order to enable others skilled in the art to apply my invention, I will now proceed to describe a mode of carrying the same into effect, reference being had to the accompanying drawing, which forms a part of this specification, and in which—

Figure 1 is a side view of part of a railroad-car to illustrate my invention.

Figure 2 is a sectional elevation of the same.

Figure 3, a transverse vertical section on the line 1-2, fig. 1.

Figures 4, 5, and 6, detached views of heater, &c., for carrying out my invention; and

Figure 7, a modification of part of the apparatus.

Similar letters refer to similar parts throughout the several views.

The body A of the car, of which a is the floor, and b b portions of the opposite sides, rests upon the usual trucks B B, and midway, or thereabouts, between the latter, and secured to the under side of the floor, is a heater, which I prefer to construct in the following manner:

A casing, C, of the square or rectangular form shown in the drawing, and enclosing the fire-chamber, rests upon and is secured to the plate d; a pipe, f, for the escape of the products of combustion, extending upwards through an opening in the floor of the car, and through the roof of the same.

The grate D, of the fire-chamber, consists of the stationary inclined side-pieces g, and the movable portion g', the latter being hung to the side-pieces by a rod, h, and prevented from falling by a rod, h', as shown in figs. 4, 5, and 6; and at the top of the casing C, and directly beneath its pipe f, is a chamber, i, across the lower end of which extend bars i', the purpose of which will be explained hereafter.

Surrounding the casing C, and secured to the plate d, are two casings, E and F, by means of which are formed two chambers, j and k, and on the outer side of the casing F are two doors, l and l', through which access may be had to the door m of the fire-chamber, and the door m' of the ash-pit.

Air is supplied to the chamber j through a short pipe, n, which extends between the casings E and F, and at the mouth of this pipe is a deflector, G, (shown in figs. 3 and 6,) hung to projections p p of the casing F, and operated from above by a rod, g, as will be explained hereafter.

The heater thus constructed, is supported by suitable hangers, c c, secured to the under side of the car.

A flat pipe, H, is arranged within the car, near the side of the same, and beneath the row of seats I I, the said pipe extending through the entire length of the car, and communicating with the hot-air chamber j of the heater, through a vertical tube, r.

Beneath each of the seats I, is a horizontal tube, J, that of one seat serving as a foot-rest for the passengers occupying the adjacent seat, and each tube communicating at one end with the pipe H, its opposite end, which is open, terminating near the middle of the car.

If the car be moving in the direction of the arrow l, fig. 6, the deflector G is adjusted, by means of the rod g, to the position shown by black lines, when, owing to the speed of the car, a forcible current of cold air will pass into the chamber j, to be there heated before it passes into the pipes H, and is distributed therefrom to different points in the car, through the horizontal tubes J.

It will be seen that these tubes serve the twofold purpose of warming-rests for the feet, and media for the delivery of hot air at points a short distance above the floor, and near to the middle of the car.

Should the interior of the car become too hot by this forcible introduction of heated air, the deflector G

may be so adjusted that the cold air admitted to the chamber *j* will be reduced in volume, when a corresponding reduction in the amount of heated air distributed into the car will take place.

If it is desirable that the introduction of heated air into the car should cease entirely, the deflector is adjusted to the position shown in red lines, fig. 6, when, if the car be still moving in the direction of the arrow 1, not only will further access of cold air to the chamber be discontinued, but such a partial vacuum will be caused therein, that the heated air in the car will be exhausted to make way for such cold air as may enter through the door-ways and windows.

It will thus be seen that when the car is in motion, the deflector can be so operated or adjusted, that through the medium of the air-heating space and distributing-pipes, the temperature of the car can be regulated at pleasure.

My invention may be carried into effect by a heater placed within the car, although I prefer to secure it outside the same, in the manner described, as, in case of collisions and other accidents, the fuel will not be apt to ignite the interior of the car. The grating *i* will also prevent the access of ignited fuel to the wood-work of the car in case of accidents.

The outer casing *F* serves as a simple jacket, and prevents the cooling of the heater in severe weather.

A suitable grating may be placed above the horizontal distributing-pipe *J*, as a rest for the feet of the passengers.

It is not essential that the deflector *G* should be hung directly to the heater in the manner described, as air may be supplied to the space *j* through a pipe carried through the roof of the car, a deflector, *G*, being hinged to the top of the pipe, on the outside of the car, in a manner which will be readily understood by reference to fig. 7. Nor does the main feature of my invention depend upon the arrangement of distributing-pipes herein described, as the heated air may be admitted to the car through orifices or gratings placed at suitable points. The smoke-pipe *f*, where it passes through the car, may be surrounded by a metal drum, *x*, secured to the floor.

I claim as my invention, and desire to secure by Letters Patent—

A deflector, so combined with the air-heating space of a railroad-car stove or heater, and with the delivery-pipes or orifices connected therewith, that when the car is in motion, the said deflector can be made to control the temperature of the car, substantially in the manner described.

In testimony whereof, I have signed my name to this specification in the presence of two subscribing witnesses.

J. E. WOOTTON.
